UNITED STATES PATENT OFFICE

JOHN VAN VORST, OF SCHENECTADY, AND GEORGE M. BAKER, OF SCOTIA, NEW YORK,
ASSIGNORS TO MOHAWK ASPHALT HEATER COMPANY, OF SCHENECTADY, NEW
YORK, A PARTNERSHIP CONSISTING OF SAID JOHN VAN VORST AND GEORGE M.
BAKER

OIL BURNER

Application filed February 16, 1927. Serial No. 168,498.

Our invention relates to vaporizing oil burners, such as are used for burning liquid hydro-carbons. These burners consist of a vaporizing coil connected to an oil supply, 5 the vapor generated in the coil being delivered through a vapor-discharge or burner nozzle, producing a flame from the heat of which the vaporizing coil becomes sufficiently heated to convert its contents into an unstable gas or vapor. A casing is provided 10 over the vaporizing coil to prevent its becoming too cold. Such casings as heretofore constructed were welded to the vaporizing coil. The vaporizing coils of such 15 burners frequently burn out and must be replaced, and with such previous constructions it was necessary to replace the casing also.

In accordance with our invention, we provide 20 a casing which is readily removable and in case the vaporizing coil is destroyed, it is only necessary to replace such coil and no other part of the burner.

The various features of novelty which 25 characterize our invention are pointed out with particularity in the claims annexed to and forming a part of this specification. For a better understanding of our invention, reference may be had to the following 30 description taken in connection with the accompanying drawing, in which Fig. 1 is a view of our burner completely assembled; Fig. 2 is a disassembled view of our burner; Fig. 3 is a perspective view of our burner 35 nozzle, and Fig. 4 is a sectional view of the burner nozzle of Fig. 3.

Referring to the drawing, a source of oil (not shown) is connected to a valve 2, to which the pipe 3 is also connected. This 40 pipe after running the full length of the burner is bent in a coil 4 back toward the left with a spring effect between the portions of the pipe extending in opposite directions. The pipe then extends back to the 45 left parallel to the pipe 3 and has connected

to the end thereof an elbow 5 into which is screwed a burner nozzle 6, which is directed toward the vaporizing coil 4. The vaporizing coil is removably supported on a base member 7. A casing 8 having end walls 9 is detachably supported on the base member and surrounds the vaporizing coil. The base member at the rear is provided with lugs 10, over which the notches 11 in the casing fit. The casing is provided with a saddle 20 which fits over the pipe for holding the pipe in place. The spring effect of the pipe where it bends back on itself takes care of the difference in expansion and contraction between the casing and the pipe, as the burner heats 50 when lighted and subsequently cools when extinguished. The casing is prevented from moving with respect to the base member by means of bolts going through holes 12 in the saddle and corresponding holes 12' in the base member. The end walls 9 of the casing are welded to the main portion of the casing. The casing is provided with openings 13 to admit air to the interior of the casing so that complete combustion will 55 take place. A hood 14 is pivotally mounted on the base member by means of bolts at the end of the casing adjacent the nozzle 6. This hood permits easy access to the burner nozzle 6, so that the same may be lighted. 60 A hollow stiffening member 15 is placed around the pipe 3.

The burner nozzle 6 has an enlarged cylindrical portion 16 which is screw-threaded into the elbow 5, and a cylindrical portion 17 of smaller diameter extending into the elbow. A hole 18 of substantially uniform diameter extends longitudinally of the nozzle. The portion 17 of smaller diameter has a plurality of holes 19 extending therethrough and communicating with the hole 18. The holes 19 are at right angles to the hole 18 and are preferably of substantially the same diameter as the hole 18. It will be readily seen that with this construction, a 70 75 80 85 90

flake of carbon entering any of the holes 18 or 19 will be blown through the nozzle, as all of these holes are of the same size. In order that our nozzle be entirely stopped up, there must be an accumulation of carbon flakes filling up the elbow 5 and covering all the holes 18 and 19 in the burner nozzle. The nozzle is shown as made of a single piece of metal. The construction of the nozzle forms the subject matter of a divisional application, Serial No. 326,178, filed December 15, 1928.

We desire it to be understood that our invention is not limited to the particular arrangement shown and described and we aim in the appended claims to cover all modifications which do not depart from the spirit and scope of our invention.

What we claim as new and desire to secure by Letters Patent of the United States is:

1. An oil burner comprising a vaporizing coil having a burner nozzle, a base member on which said vaporizing coil is removably supported, a casing surrounding said coil having end walls, said casing being detachably fastened to said base member, and a hood pivotally mounted on said base at said end of said casing adjacent said nozzle.

2. An oil burner comprising a vaporizing coil having a burner nozzle, a base member on which said vaporizing coil is removably supported, lugs on said base member, a casing surrounding said coil having end walls, said casing being detachably fastened to said base member by means of notches in said casing which engage said lugs, and a hood pivotally mounted on said base at said end of said casing adjacent said nozzle.

3. An oil burner comprising a pipe, said pipe running the full length of said burner and being bent backward in a vaporizing coil with a spring effect between the portions of the pipe extending in opposite directions, a burner nozzle at the end of said pipe, a base member on which said vaporizing coil is removably supported, a casing surrounding said nozzle having end walls, said casing being detachably fastened to said base member and having a saddle for holding said pipe in place, said saddle taking care of the difference in expansion and contraction between said casing and said pipe, and a hood pivotally mounted on said base at said end of said casing adjacent said nozzle.

4. An oil burner comprising a pipe, said pipe running the full length of said burner and being bent backward in a vaporizing coil with spring effect between the portions of the pipe extending in opposite directions, a burner nozzle at the end of said pipe, a base member on which said vaporizing coil is removably supported, lugs on said base member, a casing surrounding said coil having end walls, said casing being detachably fastened to said base member by means of

notches in said casing which engage said lugs, said casing having a saddle for holding said pipe in place, said saddle taking care of the difference in expansion and contraction between said casing and said pipe, and a hood pivotally mounted on said base at said end of said casing adjacent said nozzle.

In witness whereof, we have hereto set our hands this 14th day of February, 1927.

JOHN VAN VORST.
GEORGE M. BAKER.
